(57) **CLAIM**

The ornamental design for a pet camera, as shown and described.

DESCRIPTION

FIG. 1 is a perspective view of a pet camera showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of the pet camera showing an environmental accessory assembled to a head of the pet camera;

FIG. 10 is a perspective view of the pet camera showing the combined head and accessory separate from a body of the pet camera on an environmental wall;

FIG. 11 is a front view of the pet camera showing the bottom of the body in an illuminated state;

FIG. 12 is a right side view of the pet camera in a tilted state; and,

FIG. 13 is a right side view of the pet camera in another tilted state.

The broken lines shown in FIGS. 9 and 10 depict an environmental accessory and wall and form no part of the claimed design.

The radiating broken lines shown in FIG. 11 indicate a state of illumination for the portion from which they emanate, and form no part of the claimed design.

1 Claim, 12 Drawing Sheets
